FRICTIONAL HOLDING MEANS

John A. Obermaier, River Forest, Ill.

Application January 6, 1944, Serial No. 517,255

10 Claims. (Cl. 171—95)

1

This invention relates to adjustable devices, and has to do with means for frictionally holding in adjustment an arm or analogous member movable about an axis relative to an associated supporting member.

It is known in electrical measuring instruments, for example volt meters and electrical pyrometers, to provide an adjustable arm for assuring that the pointer of the instrument will be at the zero mark on the dial when the movable coil of the instrument is deenergized, friction means being provided for holding the arm in adjustment. The friction means commonly used is a known type of spring washer confined under pressure so as to exert pressure on the adjustable arm for holding it in pressure contact with a cooperating surface for holding the arm frictionally in adjustment. That necessitates the use of an additional part, the spring washer, which involves additional operations in assembly and production, and also involves an increase in overall height of the structure to accommodate the spring washer, all of which contributes to increased cost and is objectionable for that reason and, in certain cases, where space is restricted, is objectionable as contributing to increased overall height of the structure. While the frictional holding means of my invention is particularly suited for use in electrical measuring instruments having a movable coil, and analogous devices, it is also applicable, in its broader aspects, to a structure having an arm or analogous member pivoted for movement between two cooperating supporting members. In electric switches, for example, a spring washer of known type commonly is disposed between the switch blade and an arm of the associated supporting clip for holding the blade frictionally in adjustment, which is objectionable as involving increased operations and increased cost in material, above referred to.

My invention is directed to the provision of frictional holding means of comparatively simple and inexpensive construction and operation, in which the necessity for providing an additional part, such as the known type of spring washer referred to, is eliminated. More specifically, I provide two supporting or mounting members between which an arm or analogous member is pivoted, one of the mounting members being provided with resilient fingers cooperating with the arm and the other mounting member for frictionally holding the arm in adjustment. Further objects and advantages of my invention will appear from the detail description.

In the drawing:

2

Figure 1 is a semi-diagrammatic fragmentary plan view of a known type of electrical measuring instrument embodying the frictional holding means of my invention;

5 Figure 2 is a vertical sectional view through the instrument of Figure 1, certain parts being shown in elevation, and the instrument casing being shown fragmentarily and in section;

Figure 3 is a plan view of the bridge member 10 of the instrument of Figures 1 and 2, on an enlarged scale;

10 Figure 4 is a fragmentary sectional view taken substantially on line 4—4 of Figure 3;

Figure 5 is a sectional view taken substantially on line 5—5 of Figure 3, but showing the adjustable arm and associated parts;

15 Figure 6 is a view similar to Figure 3, but showing a modified form of bridging member;

Figure 7 is a sectional view taken substantially on line 7—7 of Figure 1;

20 Figure 8 is a fragmentary side view of a knife switch embodying the frictional holding means of my invention; and

Figure 9 is a sectional view taken substantially on line 9—9 of Figure 8.

25 In Figures 1, 2 and 5, I have illustrated the frictional holding means of my invention as applied to an electrical measuring instrument of known type, such as a volt meter or an electrical pyrometer. These instruments are well known, and a brief description of the portions of the instrument shown will suffice. This instrument comprises pole pieces 10 secured to and extending toward each other from the pole ends of a permanent magnet (not shown), the opposed faces of the pole pieces 10 being provided with arcuate recesses 11 which receive a movable coil 12. This coil 12 is mounted on a suitable frame to which are secured upper and lower arbors 13 and 14, respectively. The lower arbor 14 is pointed at its lower end and is there mounted, preferably in a jewel bearing, in the upper end of a screw 15 threaded through a lower bridge member 16, formed of copper or other suitable non-magnetic metal, suitably mounted on the pole pieces 10 and bridging the gap therebetween. A jam nut 17 is threaded on screw 15 at the lower face of bridge member 16 and cooperates with the latter for locking screw 15 in adjustment. An attaching clip 18 of substantially L shape is secured on bridge member 16 and projects upward therefrom, the upwardly extending arm of clip 18 having secured thereto, by soldering or otherwise, one end of a torsion spring 19 extending spirally about arbor 14, secured at its other end to the

downwardly extending arm of a clip 20 secured to arbor 14, conveniently by being clamped between two nuts 21 screwed on arbor 14, or in any other suitable manner. The upper arbor 13 is pointed at its upper end and is there pivoted in the lower end of a mounting screw 23, preferably in a jewel bearing member carried by this screw, threaded through an upper bridge member 24. An adjusting arm 25 is confined between the upper face of bridge member 24 and a nut 26 screwing on the screw 23 and having a hub, as will be explained more fully presently, contacting bridge member 24 for securing screw 23 in adjustment. Arm 25 is provided, at one end thereof, with a downwardly extending finger 27 to which is secured one end of a torsion spring 28 wound spirally about arbor 13 in opposite relation for torsion spring 19, the other end of torsion spring 28 being secured to the upwardly extending arm of an L-shaped clip 30 secured on arbor 13. Conveniently, clip 30 is clamped between an upper nut 31 screwing on arbor 13 and an indicator arm 32 mounted on arbor 13 and secured thereto by being clamped, together with clip 30, between nut 31 and a lower nut 33 screwed on arbor 13. The indicator arm or pointer 32 is appropriately shaped and disposed to move over a dial (not shown) of the instrument, and is provided with a balancing arm 34 weighted in a suitable manner, as by a drop of solder deposited thereon. It will be understood that the clips 18 and 20, and the clip 30, and the pointer 32 may be mounted and secured in any suitable known manner other than that disclosed. Arm 25 projects outward beyond the upper bridge member 24 at the opposite side thereof from finger 27, and is provided with an elongated slot 36. This slot 36 receives a pin 37 secured in an adjusting arm 38, at one end thereof, arm 38 being secured at its other end to a nut 39, conveniently by soldering, which is threaded on the inner end of a screw 41 passing through an opening in top wall 42 of the instrument casing, there being a fiber washer 43 interposed between arm 38 and wall 42. Nut 39 is fixed to screw 41 in a suitable manner, conveniently by being soldered thereto at 44, arm 38 being soldered to nut 39, as noted, at 45.

The instrument so far described is of known construction and operation, it being understood that the upper bridge member and the lower bridge member and parts associated therewith are formed of non-magnetic metal, as is usual. In the known instruments of this character, the adjustable arm 25 is frictionally held in adjustment by the action of a spring washer of known type, above referred to, and adjustment of arm 25 is effected by turning screw 41 in appropriate directions. It will be noted that the torsion springs 19 and 28 act in opposition, with the coil 12 mounted by needle point bearings for rotation about a vertical axis, and that the torsion spring 28 tends to turn arm 25 about the screw 23. The friction of the spring washer, in known instruments, suffices to hold arm 25 in adjustment so that, by proper adjustment of arm 25 by means of screw 41 and the parts associated therewith, the instrument can be adjusted so that the pointer 32 thereof is at the zero position of the dial when the coil 12 is deenergized.

The upper bridge member 24 is of considerable thickness and is formed of spring copper or other suitable non-magnetic metal. This bridge member 24 is mounted adjacent each end on a brass block 47 provided, at its lower end, with a reduced

screw stud 48 threaded into the associated pole piece 10. Block 47 is suitably bored and tapped from its upper end, for reception of a securing screw 49 passing through bridge member 24 and threading into block 47, there being a washer 50 interposed between the head of screw 49 and bridge member 24. Referring more particularly to Figures 1 and 3, bridge member 24 is of approximately oblong shape and is provided, at opposite sides of its longitudinal axis, with lengthwise slots 52 from which extend, at the inner ends thereof, outwardly inclined slots 53, providing two pairs of resilient fingers 54 disposed at opposite sides of the transverse axis of bridge 24, and a central hub element 55 from which extend strips 56, the latter and fingers 54 being integrally connected at their outer ends to the bridge 24. The inner ends of the fingers 54 are free from hub element 55, those of one pair of the fingers 54 being disposed at the opposite side of element 55 to those of the other pair of fingers, and the terminal portions of fingers 54 being formed at 58 for substantially point contact with an overlying element of arm 25, as will appear presently. The fingers 54 are deflected upward relative to bridge 24, and the free terminal portions thereof are bent upward at an angle, as in Figure 4.

The nut 26 is provided with a reduced inner hub 60 seating at its inner or lower end on hub element 55 of bridge 24, this nut 26 serving as a jam nut for locking the upper screw 23 in adjustment. Hub 60 of nut 26 passes through hub 61 of the adjustable arm 25, it being noted that hub 60 of nut 26 is of slightly greater height than the thickness of hub 61 of arm 25, providing slight clearance, a few thousandths of an inch, between the upper face of hub element 55 of bridge member 24 and the under face of hub 61 of arm 25, thereby providing slight vertical clearance for hub 61. When nut 26 is turned tightly onto screw 23, the under face of head 62 thereof, which is flat and projects radially outward beyond hub 60 a considerable extent, overlies hub 61 of arm 25, and also overlies the inner free end portions of resilient fingers 54 of bridge member 24. These fingers possess considerable strength and hold hub 61 of arm 25 in pressure contact with the flat under face of the flange of head 62 of nut 26, effective for holding arm 25 in adjustment about hub 60. In that manner, the resilient fingers 54 of the bridge member 24 provide means for holding adjustable arm 25 in adjustment, in conjunction with the head or flange of nut 26, avoiding necessity for providing an additional spring element, such as a spring washer of known type, and rendering possible reduction in the overall height of the bridge structure. It will be noted that the fingers 54 contact hub 61 of arm 25 at a plurality of points disposed diametrically opposite of hub 61, which guards against any tendency to tilting of this hub with possible binding thereof on hub 60 of nut 26.

In Figure 6 I have shown a modified form of bridge member 24a, this bridge member being provided with elongated U-shaped slots 52a defining resilient fingers 54a integrally connected at their outer ends to the bridge member and with their inner ends spaced at opposite sides of a central hub element 55a. The fingers 54a are deflected upward and have their inner terminal portions 58a bent upward at an angle for contact with the hub 61 of arm 25. In using this form of bridge member, when the nut 26 is turned tightly onto screw 23, the resilient fingers 54a

are forced downwardly and thereby placed under tension, in the same manner as the fingers 54 of the bridge 24 in Figures 1 to 4, inclusive, are placed under tension when nut 26 is turned fully onto screw 23. In either case, the spring fingers hold hub 61 of adjustable arm 25 in pressure contact with the inner or under face of the flange of head 62 of nut 26, effective for maintaining arm 25 in adjustment in the manner above described.

In Figures 8 and 9 I have shown a knife switch of known type embodying the frictional holding means of my invention. This switch comprises a mounting clip 65, bolted or otherwise suitably secured to an insulating base 66. The clip 65 has two upwardly extending substantially parallel arms 67 and 68 secured together in spaced apart relation by a pivot member, conveniently a rivet 69, headed at its ends. A switch arm or blade 70 is mounted between arms 67 and 68 on rivet 69 for pivotal movement thereabout. The mounting clip 65 is formed of spring metal of high electrical conductivity, preferably spring copper, and arm 68 thereof has struck therefrom a plurality of fingers 71 which are deflected inwardly so as to bear upon one side of arm 70, the other side of this arm or blade 70 being in flatwise contact with the inner face of arm 67 of the clip 65 and having a considerable area of contact therewith. The fingers 71 hold switch arm or blade 70 in pressure contact with arm 67 of the clip, effective for maintaining blade 70 in adjustment about the pivot member or rivet 69. The effective length of the rivet 69 is such as to maintain the fingers 71 under proper tension, it being understood that in Figure 9 the distance between the arms 67 and 68 of clips 65 and the inward deflection of the fingers 71 have been exaggerated for clearness of illustration. By providing the arm 68 of clip 65 with the resilient fingers 71, necessity for providing a separate spring washer, as is the present practice, is avoided, effecting a saving in material and saving in time in assembling the switch structure.

As has been indicated above, and will be understood by those skilled in this art, changes in construction and arrangement of parts of my invention may be resorted to without departing from the field and scope thereof, and I intend to include all such variations, as fall within the scope of the appended claims, in this application in which the preferred forms only of my invention have been disclosed.

I claim:

1. In frictional holding means of the class described, in combination, a supporting member, a second member positioned in closely spaced relation to said supporting member, a pivot member supported by said supporting member, and an adjustable member mounted between said supporting member and said second member for turning movement on said pivot member to different angular positions, said supporting member being formed of spring metal and having struck therefrom inwardly deflected resilient fingers bearing on the adjacent face of said adjustable member and holding the opposite face of said adjustable member in pressure contact with said second member effective to hold said adjustable member in adjustment on said pivot member.

2. In frictional holding means of the class described, in combination, a supporting member, a pivot screw in threaded engagement with said supporting member, a nut threaded on said screw

into closely spaced relation to said supporting member, and an adjustable member mounted between said supporting member and said nut for turning movement to different angular positions about the axis of said screw, said supporting member being formed of spring metal and having struck therefrom inwardly deflected resilient fingers bearing on the adjacent face of said adjustable member and holding the opposite face of said adjustable member in pressure contact with said nut effective to hold said adjustable member in adjustment on said pivot.

3. In frictional holding means of the character described, a fixed bridge member of spring metal, a nut secured to said bridge member having an inner reduced hub and an outer flange projecting radially outward beyond said hub having a flat inner face, and an adjustable arm having a hub rotatably mounted on the hub of said nut, said bridge member having integral resilient fingers bearing on the inner face of the hub of said arm maintaining the outer face thereof in pressure contact with the inner face of said flange effective for holding said arm frictionally in adjustment about the hub of said nut.

4. In frictional holding means of the character described, a fixed bridge member of spring metal, a nut secured to said bridge member having an inner reduced hub and an outer flange projecting radially outward beyond said hub having a flat inner face, and an adjustable arm having a hub rotatably mounted on the hub of said nut, said bridge member having integral resilient fingers bearing on the inner face of the hub of said arm at diametrically opposite points thereof maintaining the outer face of the hub of said arm in pressure contact with the inner face of said flange effective for holding said arm frictionally in adjustment about the hub of said nut.

5. In frictional holding means of the character described, a fixed bridge member of spring metal, a nut secured to said bridge member having an inner reduced hub and an outer flange projecting radially outward beyond said hub having a flat inner face, and an adjustable arm having a hub rotatably mounted on the hub of said nut, the latter hub being of slightly greater height than the thickness of the hub of said arm providing slight vertical clearance therefor, said bridge member being slotted thereby providing resilient fingers integral therewith, said fingers being deflected toward the flange of said nut and bearing on the inner face of the hub of said arm maintaining the outer face thereof in pressure contact with the inner face of said flange effective for holding said arm frictionally in adjustment about the hub of said nut.

6. In frictional holding means of the character described, a fixed bridge member of spring metal, a nut secured to said bridge member having an inner reduced hub and an outer flange projecting radially outward beyond said hub having a flat inner face, and an adjustable arm having a hub rotatably mounted on the hub of said nut, the latter hub being of slightly greater height than the thickness of the hub of said arm providing slight vertical clearance therefor, said bridge member being slotted thereby providing resilient fingers integral therewith at their outer ends and shaped at their inner ends for point contact with the hub of said arm, said fingers being deflected toward the flange of said nut and bearing on the inner face of the hub of said arm maintaining the outer face thereof in pressure con-

tact with the inner face of said flange effective for holding said arm frictionally in adjustment about the hub of said nut.

7. In a measuring instrument, a coil pivoted for rotation about an axis, a fixed bridge member, a screw threaded through said bridge member providing a pivot for said coil, a nut threaded on said screw locking it to said bridge member, said nut having an inner reduced hub seating at its inner end on said bridge member and an outer flange projecting radially outward beyond said hub having a flat inner face, an adjustable arm having a hub rotatably mounted on the hub of said nut, the latter hub being of slightly greater height than the thickness of the hub of said arm providing slight vertical clearance therefor, and a torsion spring anchored at one end to said coil and at its other end to said arm tending to turn the latter about the hub of said nut, said bridge member being formed of spring metal and slotted thereby providing resilient fingers integral therewith at their outer ends and free therefrom at their inner ends, said fingers being deflected toward the flange of said nut and bearing on the inner face of the hub of said arm maintaining the outer face thereof in pressure contact with the inner face of said flange effective for holding said arm frictionally in adjustment about the hub of said nut.

8. In a measuring instrument, a coil pivoted for rotation about an axis, a fixed bridge member of spring metal slotted lengthwise at opposite sides of its longitudinal axis to provide a central hub and two pairs of resilient fingers integral with said bridge member at their outer ends having their inner ends free from said bridge member with the inner ends of one pair of fingers disposed at one side and the inner ends of the other pair of fingers disposed at the opposite side of the transverse axis of said bridge member, a screw threaded through said hub providing a pivot for said coil, a nut threaded on said screw locking it to the hub of said bridge member, said nut having an inner reduced hub seating at its inner

end on the hub of said bridge member and an outer flange projecting radially outward beyond the hub of said nut having a flat inner face, an adjustable arm having a hub rotatably mounted on the hub of said nut, the latter hub being of slightly greater height than the thickness of the hub of said arm providing slight vertical clearance therefor, and a torsion spring anchored at one end to said coil and at its other end to said arm tending to turn the latter about the hub of said nut, said fingers being deflected toward the flange of said nut and bearing on the inner face of the hub of said arm maintaining the outer face thereof in pressure contact with the inner face of said flange effective for holding said arm frictionally in adjustment about the hub of said nut.

9. In frictional holding means of the character described, a mounting clip having two substantially parallel supporting arms, a pivot member securing said arms together in spaced relation, and a member mounted between said arms on said pivot member for turning movement about the latter, said member having a flat surface of appreciable area in contact with one of said arms, the other of said arms being formed of spring metal and having struck therefrom inwardly deflected resilient fingers bearing on the opposite face of said member and holding said flat surface thereof in pressure contact with said one arm effective for holding said member frictionally in adjustment about said pivot member.

10. In a device of the class described, in combination, a pair of adjacent members, a pivot supported by at least one of said members, and an adjustable member mounted between said adjacent members on said pivot for turning movement about the axis of the pivot, one of said adjacent members being formed of spring metal and having struck therefrom inwardly deflected resilient fingers adapted to bear on the adjacent face of the adjustable member to hold said adjustable member in angular adjustment.

JOHN A. OBERMAIER.
